SAMUEL D. SIBLEY, OF DETROIT, MICHIGAN, ASSIGNOR, BY MESNE ASSIGNMENTS, TO SEMET-SOLVAY COMPANY, OF SOLVAY, NEW YORK, A CORPORATION OF NEW YORK.

GUIDING DEVICE FOR CONVEYER-BELTS.

1,192,128.

Specification of Letters Patent. Patented July 25, 1916.

Application filed June 24, 1915. Serial No. 36,046.

To all whom it may concern:

Be it known that I, SAMUEL D. SIBLEY, a citizen of the United States, residing at Detroit, in the county of Wayne and State 5 of Michigan, have invented a new and Improved Guiding Device for Conveyer-Belts, of which the following is a specification.

As is well known in the operation of conveyer belts, usually troughed, on which loads 10 of material are carried, it is difficult to keep the belt properly centered on the supporting idlers, as it has a tendency to work to one side or the other. This sidewise motion of the belt has been heretofore prevented by 15 rollers adapted to bear against the edges of the belt. The friction of the belt against these, however, causes material wear of the belt edge and its ultimate destruction.

The object of my improvements is to ob- 20 viate this difficulty and provide a means for centering or guiding the belt automatically and without wear. This I accomplish by means of idlers located on opposite sides of 25 and underneath the belt, upon which the belt rests in its travel. These are so mounted that, when the belt begins to move to one 30 side or the other from its central line of travel, the idlers are caused, by the action of the belt, to take such a position in relation thereto, that the rotary movement of the 35 idlers operates to shift the belt back to its proper position.

The invention will be best understood by reference to the accompanying drawings, 40 illustrating an embodiment thereof, Figure 1 of which shows a plan view of the device partially in section on the line 1—1, Fig. 2; Fig. 2 shows a partial section on the line 2—2, Fig. 1; and Fig. 3 shows a sectional view on the line 3—3, Fig. 2.

Referring to the drawings, A, indicates a conveyer belt supported in the usual manner upon idlers (not shown in the drawings). Along the sides of and underneath the belt, 45 A, are located guiding idlers, B, B', associated in pairs and so positioned that when the belt is in its normal centered position it rests equally and, preferably, upon a part only of the bearing surface of each of the 50 idlers. The idlers, B, B', are carried on shafts, C, C', which at their lower ends are pivotally mounted and free to rotate in sockets, d, d, formed in, or secured to, a support, D. The shafts, C, C', are curved or 55 positioned in such manner that when they

are rotated in their sockets the idlers carried thereby will be swung forward or backward as the case may be, and thus the angular relation of their bearing surfaces to the belt will be changed. To the lower portion of 60 each of the shafts, C, C', is rigidly secured an arm, e, e, which, at their free ends are connected by a rod, E, so that when one of the idlers as, B, is swung in either direction by the rotation of its shaft, C, the other 65 idler, B', will at the same time, and to the same extent, be swung in the opposite direction.

The operation of the device is as follows: Normally, when the belt is properly cen- 70 tered, it will lie to the same extent on each of the idlers, B, B', and the bearing surfaces of these will be in a plane at right angles to the center line of the belt. If now the belt begins to move to one side or the other and, 75 hence, to creep up one of the idlers as, B, more of the bearing surface of the idler, B, will be contacted by the belt and less of that of the idler, B'. Thus a greater weight is put on the idler, B, and this is swung for- 80 ward in the direction of movement of the belt, such swinging being permitted through the rotation of the shaft, C, in its bearing. At the same time through the action of the arms, e, e, and the connecting rod, E, the 85 idler, B', is swung to the same extent in the opposite direction. The bearing surfaces of the idlers, B, B', instead of being in a plane at right angles to the center line of the belt, now lie at an angle thereto and the direc- 90 tion of rotation of the idler, B, is toward the center line of the belt and that of the idler, B', away therefrom, so that the action of both idlers is to move the belt back to its central line of travel until it is properly cen- 95 tered. When the belt is centered the idlers resume their normal position because of the increased pressure on the idler, B'. In case the belt creeps up on the idler, B', a reverse movement of the idlers takes place and the 100 belt is moved back to its central line of travel, in the same manner as above described.

In order to quickly correct any abnormal side movement of the belt of such extent as 105 to cause it to move entirely across one or the other of the idlers, B, B', I provide auxiliary pulleys, b, b', which are rotatably mounted on the shafts, C, C', at the outer ends of the idlers, B, B'. Each of the pulleys, b, b', is 110

provided with a clutch member, c , c , which are held, as by means of coiled springs, S , in engagement with corresponding clutch members, or equivalent holding means, c' , c' , 5 rigidly secured to the shafts, C , C' , so that the pulleys, b , b' , cannot be rotated, or can be rotated only with difficulty, so long as the clutch members are engaged. In case the belt moves so far to one side as to contact 10 with one or the other of the pulleys, as b , the friction of the belt on the surface of the non-rotating pulley operates to quickly swing the shaft, C , and idler, B , into angular relation with the belt. As the pulley is 15 swung around, so that its axis is no longer at right angles to the center line of the belt, the friction of the belt on its surface pushes it forward so as to disengage the clutch members. The pulley then revolves, thus preventing 20 abrasion of the belt and assisting the idler, B , in centering the belt, until the belt has moved off the pulley. When the belt rides up onto the corresponding pulley, b' , on the other side, the action will be the 25 same but in the opposite direction. Preferably the pulleys, b , b' , are made of wood or other non-abrasive material. Thus by means of my invention, any sidewise movement of the belt is automatically corrected 30 and the belt is kept to a central line of travel, the advantages of which will be readily understood by those skilled in the art.

What I claim as new and desire to secure 35 by Letters Patent is:

1. The combination with a conveyer belt, of a guiding idler located at the side of and underneath the belt and adapted to be moved into angular relation with the belt by friction of the belt thereon, a shaft for said 40

idler, and a normally non-rotating pulley, mounted on the same shaft with the idler and adapted to be contacted by the belt when the belt travels sidewise entirely across the idler and to be moved into a rotating position by the pressure of the belt thereon. 45

2. The combination with a conveyer belt, of a guiding idler located at the side of and underneath the belt and adapted to be moved into angular relation with the belt by friction of the belt thereon, an independently rotatable pulley mounted on the same shaft as the idler and adapted to be contacted by the belt when the latter, in departing from its center line of travel, moves entirely 50 across the idler, and means for retarding the rotation of the pulley.

3. The combination with a conveyer belt, of a guiding idler located at the side of and underneath the belt and adapted to be moved 55 into angular relation with the belt by friction of the belt thereon, an independently rotatable pulley mounted on the same shaft as the idler and adapted to be contacted by the belt when the latter in departing from 60 its center line of travel moves entirely across the idler, means for retarding or preventing the rotation of the pulley when in its normal position, and means for causing the pulley to rotate when its axis is moved into 65 angular relation with the center line of the belt.

In testimony whereof, I have hereunto subscribed my name, this 15 day of June A. D., 1915.

SAMUEL D. SIBLEY.
